AIRCRAFT ARMAMENT

Croydon H. A. Hartley, Garden City, N. Y., assignor to Republic Aviation Corporation, a corporation of Delaware

Application October 10, 1940, Serial No. 360,555

3 Claims. (Cl. 89—1.5)

This invention relates to aircraft armament and more particularly to bomb racks for airplanes.

One of the objects of the invention is to provide an improved bomb release mechanism of simple and rugged construction, reliably operative in extended service.

Another object is to provide a bomb releasing rack having a release mechanism capable of carrying and discharging a relatively heavy bomb and requiring only a minimum of force to actuate the release, thereby to obviate any risk of jamming and to minimize friction and wear of the parts.

The invention has reference to bomb racks such as shown in the copending application of Pishvanov, Serial No. 210,628 (Patent No. 2,278,482, granted April 7, 1942), filed May 28, 1938, in which mechanism is provided for releasing the series of bombs on the rack, either one at a time, in rapid sequence, or in salvo.

In the drawing

Figures 1 and 2 are elevational views partly in section of the bomb release mechanism, Figure 1 showing the mechanism in cocked position and Figure 2 showing the mechanism after release of the bomb.

Figure 3 is a top elevational view of the mechanism, and,

Figure 4 is a transverse sectional view taken on line 4—4 of Figure 1.

An elongate frame 6 provides support for the operating and releasing mechanism of the bomb rack and includes a pair of angle members 7 in between which the release mechanism is arranged. The frame 6 is provided to support a series of bomb release units, one of which is shown, these units being arranged at intervals along the frame 6.

Each release unit includes a hook or catch 8 having a tongue 9 on which the bomb is hung, being retained thereon in the cocked position of the mechanism by the edges of a slot 10 formed in the depending flange of each angle member 7. The hook 8 is preferably in the form of a bellcrank having an upstanding arm 11 arranged substantially at right angles to the tongue 9 and is pivoted at 12 to swing between cocked and releasing position, the latter being defined by engagement of a shoulder 13 of the hook with a stop pin 14.

The upper portion of the arm 11 has a circular cutout portion 15 which forms a pivotal connection for a sear or trigger 16 having a correspondingly formed portion 17 fitting said cutout. The

cutout 15 is directed radially at 19 to form a stop engageable with a shoulder 20 formed on the sear 16. A spring 21 is arranged to urge the sear 16 to rotate about its pivot 17 relative to the hook 8 with the stops 19, 20 in engagement to limit this swing.

The sear 16 has a latching shoulder 22 intermediate its ends adapted to engage a fixed member, herein a bearing block 23, to releasably hold the hook 8 in cocked position as shown in Figure 1 with a bomb hanging on the tongue 9. A spring 24, acting on the hook 8, is arranged to urge the latter to release position. The spring 24 substitutes for the weight of the bomb in the cocking of the mechanism before the bomb weight is supported by the tongue 9.

The bearing block 23 is secured to the upper flanges of the angles 7 and rotatably supports a shaft 25 constituting part of the operating mechanism for actuating the bomb releasing units. The shaft 25 carries a cam 26 cooperating with a cam follower 27, the latter being arranged to engage the free end of the sear 16. The follower 27 is preferably an elongate spring arranged longitudinally on the frame 6 and secured at one end thereto. The free end of the spring 27 is bent laterally to form a depending lug 28 reaching between the frame angles 7 for engagement with the sear 16.

The invention contemplates the use of suitable mechanism such, for example, as that shown in the aforesaid pending application, by which to rotate the shaft 25 a predetermined degree. As aforesaid, it is intended that the bomb rack of the invention have provision for a series of bombs, usually five, there being a corresponding releasing unit provided for each bomb along the rack, the operating mechanism including shaft 25 serving to successively actuate each bomb release unit so as to discharge the bombs one after the other in a prescribed order. For this purpose each cam 26 of the series has its high point angularly spaced about the shaft 25 so that all of the release units will be actuated during one complete revolution of the shaft.

To cock the mechanism, the bomb is brought into place with its holding eyelet adjacent the tongue 9 and the hook 8 is pressed upwardly, carrying with it the sear 16 until the latter has its shoulder 22 latched behind the bearing block 23, the spring 24 acting to retain said engagement until the weight of the bomb rests on the hook. As the shaft 25 is rotated by its operating mechanism, the high point of cam 26 presses the spring follower 27 downwardly until the shoul-

der 22 is free of the block 23, whence the hook 8 swings about its pivot under influence of the bomb weight and spring 24 to the position shown in Figure 2 at which the bomb is released. As the follower 27 presses the sear 16 to the position shown in the dot and dash outline in Figure 1, the latter is swung about its pivot 17, during which the spring 21 is compressed. After releasing the bomb, the spring 21 restores the sear 16 to the position defined by the stops 19, 20, in readiness for cocking.

It will be seen that the form and arrangement of the spring follower 27 provides a lateral guide for the lug 28 and thus eliminates any lateral reaction on the sear 16 such as would be had with the cam 26 directly engaging the sear. The shoulder 22, being engaged with a fixed member such as the block 23, eliminates any tendency to laterally displace the sear were same cooperating with a moving member. The pivotal association of the sear 16 and hook 8, as shown, provides an economic and rugged construction and permits the arrangement of the parts between the closely associated flanges of the frame 6.

Having now made certain the nature and purposes of my invention, and at least one mode of executing same, in such manner as to enable any-one skilled in the art to which it apertains, to make and use same, as required by the statutes, that which I claim as my property, and desire to secure by Letters Patent of the United States is:

1. A bomb-rack, comprising an elongate frame, a plurality of hooks pivotally mounted up-

on the frame, each adapted to suspend a bomb and adapted to be swung by the weight of the bomb to release said bomb therefrom, latching means normally restraining swinging movement of the hooks, a control shaft rotatably mounted along the frame and driving means for rotating the shaft to move successively the latching means out of restraining position with respect to the hooks; bearings for the shaft fixed on the frame one above each hook and sears articulated to the hooks and having latching shoulders adapted to press normally against one side of said bearings so as to latch the hooks in cocked position and a releasing mechanism, including cams fixed upon the shaft on the opposite side of the bearings for depressing successively the sears out of cocked position when the shaft is rotated.

2. In a bomb-rack as recited in claim 1, a plurality of movable members interposed between said cams and the free ends of said sears and adapted to cooperate therewith to absorb lateral thrusts arising from the cams while successively depressing the sears out of cocked position when the shaft is rotated.

3. In a bomb-rack as recited in claim 1, flat resilient members interposed between said cams and the free end of said sears, said members being organized with said cams to act as cam-followers and being also adapted to absorb and dissipate the lateral thrusts imparted by said cams while successively depressing the sears out of cocked-position when the control shaft is rotated.

CROYDON H. A. HARTLEY.
